UNITED STATES PATENT OFFICE.

TEDRICK D. BENDURE AND JOSEPH S. BENDURE, OF LONDON, OHIO.

SAMPLE-HOLDER.

SPECIFICATION forming part of Letters Patent No. 633,781, dated September 26, 1899.

Application filed March 8, 1899. Serial No. 708,186. (No model.)

To all whom it may concern:

Be it known that we, TEDRICK D. BENDURE and JOSEPH S. BENDURE, citizens of the United States, residing at London, in the county of Madison and State of Ohio, have invented a certain new and useful Improvement in Sample-Holders, of which the following is a specification.

Our invention relates to the improvement of sample holding and displaying devices, and has particular relation to devices for holding and displaying samples of dry goods.

The objects of our invention are to provide a neat, simple, and effective device for holding and displaying samples of textural fabrics and admitting of the same being drawn out of the holder and cut off in such lengths as may be desirable, to so construct and arrange the parts of said device as to adapt it for insertion within a bolt of goods corresponding with the sample, and to produce other improvements in details of construction and arrangement of parts, which will be more fully pointed out hereinafter. These objects we accomplish in the manner illustrated in the accompanying drawings, in which—

Figure 1 is a view in perspective of our improved holding device. Fig. 2 is a detail view in perspective of the outer end portion of the same. Fig. 3 is a central longitudinal section, and Fig. 4 is a view in perspective of a bolt of goods having our improved sample-holder supported therein.

Similar numerals refer to similar parts throughout the several views.

In carrying out our invention we employ an oblong holding device, the body 1 of which consists of a strip of sheet metal or other similar material, said strip being doubled or folded slightly beyond the center of its length to result in the production of upper and lower plates or leaves, such as are indicated at 2 and 3, these upper and lower members being parallel with each other. The rear portion 45 of the upper member is, as indicated at 4, preferably raised to a greater distance above the lower member than the forward portion thereof. As indicated at 5, the base or lower member of the holder is provided with upturned or flanged sides, these sides, in conjunction with the upper and lower members of the device, forming substantially an oblong

box ing-casing. The forward end of the lower member of the holder, as shown, is turned upward, said upturned portion having its 55 sides doubled or bent to form keepers, within which is adapted to be held a card or indicator-plate 6, on which may be marked the price, name, or quality of the goods contained in the holder. As shown at 7, the upper member 60 3 of the holder is in its forward portion preferably provided with two or more parallel slotted openings.

In utilizing our improved sample holding and displaying device a sample strip of the 65 goods of desired length is, as indicated at 8, arranged between the upper and lower members of the casing or holder described, the rear and higher portion of the casing 4 being employed as a storage-space, wherein the surplus 70 material may be contained in folds, as indicated more clearly in Fig. 3. From this rear portion of the holder the strip 8 extends forwardly between the members 2 and 3, being threaded, as shown, through the slotted openings 75 7, for the purpose of creating a desirable friction when the same is pulled outward. The outer portion of the strip is designed, as indicated, to run over and drop downward in front of the upturned outer end portion of 80 the holder, thereby displaying from the forward end of the casing a portion of the goods contained therein.

It is evident that the sample strip may be inserted or placed in position within the case 85 or holder heretofore described by raising the upper leaf or member 1 of the holder, which owing to its spring character will readily return to its horizontal position after the insertion and arrangement of the goods.

While it is obvious that the above-described holder may be employed independent of any support therefor, the same is particularly designed, as indicated in Fig. 4 of the drawings, to have its body portion inserted 95 within the center of a bolt of goods, such as is indicated at 9, in such manner as to cause its outer end portion to project on the outer side of the bolt, thereby admitting of the depending end of the sample strip being displayed at the end of said bolt.

From the above-described construction and operation it will readily be seen that the sample-holder will provide a source from which

samples of goods may be cut without mutilating the goods forming the bolt and that said holder and displaying device will also provide an exceedingly convenient means of displaying the character of the goods contained in the bolt.

It will be observed that the construction of our device is simple and that the same may be produced at a reasonable cost of manufacture in a neat and attractive form.

Having now fully described our invention, what we claim, and desire to secure by Letters Patent, is—

A sample-holder comprising a single blank

bent upon itself to form upper and lower integral plates, said upper plate having its forward portion provided with transverse parallel slots and having its rear portion raised to provide an enlarged space between said plates and said lower plate having side flanges bent toward said upper plate and an upturned end provided with means for holding a card, substantially as specified.

TEDRICK D. BENDURE.

JOSEPH S. BENDURE.
